METHOD AND MEANS FOR ATTACHING
SPONGY MATERIAL TO BACKINGS OR
HOLDERS

Sidney P. Vaughn, San Diego, Calif.

Application November 25, 1936, Serial No. 112,786

8 Claims. (Cl. 300—21)

(Granted under the act of March 3, 1883, as
amended April 30, 1928; 370 O. G. 757)

This invention relates to cleaning devices generally, but has special reference to a novel method and means for attaching cleaning material, for example, cellulose sponge or analogous compressible material to a holder or backing.

A further object of the invention resides in the provision of a method for securing backs to cleaning material at reduced cost, and which method provides for ease of assembly and yet produces a neat and attractive article.

Another object of the invention consists in providing a method of adhesively securing compressible material to a backing in an expeditious manner and in which method the backs are exposed to the atmosphere so as to permit rapid evaporation of the moisture in the adhesive as well as the escape of fumes.

A still further object of the invention consists in adhesively attaching compressible material to a backing in such manner that the article, such as a mop, may be boiled and otherwise cleaned and disinfected without breaking down the connection between the sponge and its backing.

Another object of the invention resides in the provision of a simple and inexpensive method of attaching compressible cleaning material to a backing of the fountain brush type.

Other objects and advantages of the invention will be apparent from the following description when taken in connection with the accompanying drawing, in which,

Figure 1 is a perspective view, partly in section, of two of the articles clamped together during the drying or setting process.

Figure 2 is a transverse sectional view of a backing and sponge element in inverted position before being pressed together and indicating in dotted lines a second assembly adapted to be compressed against the lower one as indicated in Figure 1.

Figure 3 is a transverse sectional view of a slightly modified form of backing and method of attaching the same to a block of sponge material, and

Figure 4 is a sectional view through a further modification of mop in which cleaning fluid such as water is adapted to be fed to the sponge through the handle.

Referring to the drawing in greater detail and particularly to Figures 1 and 2, the numeral 1 designates an elongated block of sponge material such as cellulose sponge. This material, which forms the working part of the mop, is shown as substantially rectangular in cross-section but it is

to be understood that this shape may be varied to suit requirements.

The backing for the sponge block is indicated in Figures 1 and 2 by the numeral 2 and is shown as comprising an elongated metal plate of slightly less length and breadth than the sponge block 1. The plate 2 is formed with a continuous, substantially right angular flange or skirt 3 joined to the plate portion of the backing by the arcuate portion 4.

The backing member 2 is preferably secured to the sponge material by means of cellulose adhesive or other waterproof adherent, and in order to produce a firm and permanent connection between these parts a plate 5 is mounted in the backing. This plate is shown as formed of sheet metal provided with perforations 6, but it is to be understood that wire mesh or other foraminous sheet material may be employed. The perforated plate is preferably shaped to substantially the cross-sectional shape of the backing 2 and preferably has its end and side edges gripped by a crimped portion 7 formed on the flange 3. When a sheet metal plate is employed as the interlocking member for the waterproof adhesive, indicated by numeral 8, it is desirable that the plate be spaced slightly from the backing so as to facilitate passage of the adhesive through the perforations. If wire mesh is employed however this spacing of the parts becomes less important inasmuch as the adhesive can more readily pass around the wires forming the interstices.

In assembling the backing and mop material the adhesive 8 is placed in the backings as indicated in Figure 2 and the sponge block is placed on the flanges 3 with the latter evenly spaced from the edges of the block; or if preferred the backs may be inverted and placed on top of the sponge block since the adhesive is fairly viscous. The assembled elements are then placed in pairs as indicated in dotted lines in Figure 2 and pressed together so as to bring the sponge material into firm contact with plate 5 and with the adhesive in those areas circumscribed by the flanges 3. The pair of articles are held in their compressed condition by a band of tough paper or the like 9 which may be passed around the paired articles and have its ends secured by adhesive or otherwise. When compressed as indicated in Figure 1 the flanges 3 become embedded in the sponge material and thus provide a seal which prevents the escape of the adhesive from the interior of the backing. This manner of clamping the articles avoids completely inclosing the sponge material and provides for free circu-

lation of air through the pores of the sponge to facilitate evaporation of moisture in the adhesive.

Some of the adhesive passes through the perforations 6 of plate 5, or through the interstices of the fabric, if wire mesh is used, and when it sets serves to securely and permanently lock the sponge to the backing. Such a connection is not affected by hot water or the like, and hence the mops as thus constructed may be boiled if desired without damage.

In Figure 3 the block of sponge material 1 is shown as connected to a backing 10 in a somewhat different manner. In this form of the invention the backing 10, which may be formed of wood or metal, is provided with a roughened surface 11 at the base of the flanges 12. The adhesive is applied to the recessed portion of the backing as in the form previously described, and the backing is then applied to the upper or lower surface of the sponge block 1.

After the sponge and backing are brought into contact a rigid plate 13 of wood or the like is placed against the opposite face of the sponge and the members 10 and 13 pressed toward each other sufficiently to bring the surface of the sponge into contact with the adhesive and the roughened surface 11 of the backing. A band 9, similar to that shown in Figure 1, is then passed around the compressed members and its ends brought together and secured in any desired manner. The sponge is thus held tightly against the roughened surface 11 until such time as the adhesive sets, and it is to be noted that the roughened surface greatly enhances the strength of the connection between the two parts.

In assembling and securing the backing and sponge block, either in the manner depicted in Figures 1 and 2 or that shown in Figure 3, the members may be pressed together by hand or in a press of any suitable form, and automatic machinery may be employed to attach the band 9 while the parts are in compressed condition.

In Figure 4 the invention is shown as applied to mop or brush of the fountain type. In this construction the sponge block 1 is adhesively attached to a backing 20 provided with flanges 21 and a roughened inner surface 22. The backing 20 is provided with a central flanged opening 23 in which is mounted a tubular member 24 provided with a perforated inner end 25, and with threads 26 on its outer end for the reception of a hollow handle or hose connection.

The sponge block and backing of Figure 4 are assembled and held in compressed condition in the manner indicated in connection with either of the forms heretofore described. It should be mentioned however that the perforated end 25 of tube 24 is spaced inwardly of surface 22 a distance at least as great as the height of flanges 21. By thus proportioning the parts it will be apparent that any liability of the adhesive entering the perforations of cap 25 is avoided.

From the foregoing description and the attached drawing it will be apparent to those skilled in the art that I have devised an extremely simple and inexpensive means and method for permanently attaching backings to sponge material or other cleaning material; that the resulting product is neat and attractive in appearance; that the assembled parts are firmly held in compressed condition until the adhesive sets and are so held as to permit free circulation of air to expedite the setting of the adhesive;

and that the invention is adapted to mops of the fountain brush type as well as other types.

In accordance with the patent statutes I have described what I now consider to be preferred embodiments of the invention, but various changes and modifications can be made without departing from the spirit of the invention, and all such changes and modifications are intended to be included within the scope of the appended claims.

The invention described herein may be manufactured and used by the Government of the United States of America for governmental purposes without the payment of any royalties thereon or therefor.

What I claim is:

1. The method of adhesively securing spongy material to a backing which comprises mounting a sheet of foraminous material in spaced relation to the backing, interposing adhesive material between the spongy material and sheet, and pressing the spongy material and backing together so that the adhesive is caused to pass in part through the openings in the foraminous sheet and become interlocked therewith.

2. The method of adhesively securing spongy material to a backing which comprises securing a sheet of foraminous material in a backing having walls to retain the adhesive, placing adhesive material on the sheet, pressing the spongy material against the foraminous sheet and the walls of the backing so that the part within the walls contacts the adhesive and forces a portion thereof into and about the foraminous sheet and the part resting against the walls functions as a seal to prevent the escape of the adhesive.

3. A cleaning unit comprising a flanged backing, a sheet of foraminous material anchored in said backing, adhesive in the backing in contact with the foraminous sheet, and spongy material having a compressed portion in the backing in contact with the adhesive and foraminous sheet, whereby portions of the adhesive are caused to interlock with the sheet.

4. A cleaning unit comprising a flanged backing, a perforated strip of sheet metal anchored in the backing, adhesive in the backing in contact with the perforated strip, and spongy material having a compressed portion in the backing in contact with the adhesive and perforated strip, whereby portions of the adhesive are caused to interlock with the sheet.

5. A cleaning unit comprising a flanged backing, a sheet of foraminous material anchored in the backing in spaced relation to the base thereof, adhesive in the backing in contact with the foraminous sheet, and spongy material having a compressed portion in the backing in contact with the adhesive and foraminous sheet, whereby portions of the adhesive are caused to interlock with the sheet.

6. A cleaning unit comprising a substantially dish-shaped backing, a sheet of foraminous material in the backing and substantially co-extensive therewith, means on the backing for gripping the edge of said sheet, adhesive in the backing in contact with the foraminous material, and a block of spongy material having a compressed portion in the backing in contact with the adhesive and foraminous sheet, whereby portions of the adhesive are caused to interlock with the sheet.

7. A cleaning unit of the fountain brush type comprising a flanged backing having a central aperture therein, a tube mounted in said aperture, an apertured closure on the inner end of

said tube, said closure being spaced from the bottom of the backing a distance at least as great as the height of the backing flange, adhesive in the backing, and a block of cleaning material having a portion pressed into contact with the adhesive and backing.

5 8. A cleaning unit comprising a flanged backing, a sheet of foraminous material in the backing, the free edge of the flange being doubled

over the edge of the foraminous material to secure the latter in position, adhesive in the backing in contact with the foraminous sheet, and spongy material having a compressed portion in the backing in contact with the adhesive and foraminous sheet, whereby portions of the adhesive are caused to interlock with the sheet.

5 SIDNEY P. VAUGHN.

Patent No. 2,150,196

Granted March 14, 1939

SIDNEY P. VAUGHN

The above entitled patent was extended October 2, 1951, under the provisions of the Act of June 30, 1950, for 7 years and 174 days from the expiration of the original term thereof.

Commissioner of Patents.
